UNITED STATES PATENT OFFICE.

CHARLES H. AUSTIN, OF PALMYRA, NEW YORK.

ELECTRIC CURLING-IRON HEATER.

1,090,672.

Specification of Letters Patent. Patented Mar. 17, 1914.

Application filed October 21, 1912. Serial No. 726,959.

To all whom it may concern:

Be it known that I, CHARLES H. AUSTIN, a citizen of the United States, residing at Palmyra, in the county of Wayne, State of New York, have invented certain new and useful Improvements in Electric Curling-Iron Heaters; and I do hereby declare the following to be a full, clear, and exact description of the invention, such as will enable others skilled in the art to which it appertains to make and use the same.

This invention relates to electric heaters and more particularly to an electric curling iron heater designed to be attached to an electric light socket in the manner of an ordinary incandescent lamp, after the latter is removed therefrom, whereby the device may be carried in a suit case or otherwise in a very convenient manner and always be usefully at hand.

The essential object of the invention resides in the provision of a device of this character constructed of a few, simple and novel parts arranged to receive and hold a curling iron in an upright or horizontal position or at an angle, while novel means are also provided for grasping the heater when attaching or removing the iron, without burning the hands.

With the above and other objects in view, the invention resides more particularly in the peculiar combination and arrangement of parts as will be illustrated as a preferred embodiment in the accompanying drawings and described in the specification, although the invention is protected for all desirable changes and uses as come within the scope of the invention as claimed.

Figure 1 is an elevational view of the device, showing a curling iron held in the heater. Fig. 2 is a vertical sectional view of the device. Fig. 3 is a cross sectional view taken on the line 3—3 of Fig. 1. Fig. 4 is an end elevation of the device looking toward the open end.

As illustrated, the preferred embodiment of the improved electric heater for heating curling irons or the like comprises an exterior porcelain casing 10 open at its ends and having a screw socket plug 11 fitted in one end thereof. This plug is of the usual construction and embodies a threaded

thimble 12 which is attached to a porcelain stud 13 having an inner portion or flange 14 secured to or formed with the casing. 55 One terminal 15 extends through the central portion of the stud while the other terminal 16 extends along just inside the thimble 12 and makes contact with the thimble, which latter is of current conducting material. Fitted below the porcelain stud 13 is an insulating cap 17 formed of asbestos or mica while the terminals 15 and 16 connect with a tubular heating coil 18 formed of resistance wire whereby an interior receiving space 19 is provided for heating the curling iron 20. The opposite end of the casing is reduced in size to form a neck portion 21 preventing displacement of the heating coils and a ring or collar 22 is secured in 70 spaced relation at a plurality of points to the neck portion by means of screws 23 and intermediate non-conducting sleeve 24 and owing to the fact that the ring or collar is of wood, it may be grasped by the user 75 without burning the hands and thus the curling iron may be conveniently fitted in and removed from the heater. A leaf spring 25 is also provided and secured to the neck portion of the casing to securely hold the 80 iron in position whether the heater is disposed horizontally, vertically or in an inclined position and this spring has a curved arm 26 extending into the heating space and an arm 27 extending outwardly while 85 an inwardly extending projection 28 having a concaved engaging face is provided to more tightly grip the iron at the neck portion of the heater.

From the foregoing description in connection with the accompanying drawings, it will be seen that in the use of the device it is simply inserted in an electric light socket and the current being turned on, the iron is shoved into the heater and held by 95 the spring and by reason of the heat generated by the resistance material, the iron will also be heated for use in the ordinary manner.

I claim:

An electric heater embodying a casing of non-conducting material having a socket plug at one end thereof, a cylindrical resistance element within the casing and hav-

ing its terminals leading to the plug, a non-heat-conducting grasping member at the other end of the casing and a spring carried by the casing for holding a curling iron 5 therein, said spring having opposite branches extending within and without the heating space within the resistance element.

In testimony whereof, I affix my signature, in the presence of two witnesses.

CHARLES H. AUSTIN.
